ATTORNEYS

UNITED STATES PATENT OFFICE.

HARRY ABRAMSON, OF PHILADELPHIA, PENNSYLVANIA.

DESIGN FOR A SAD-IRON GRATE.

43,492.

Specification for Design.

Patented Feb. 4. 1913.

Application filed October 31, 1912. Serial No. 728,942. Term of patent 14 years.

To all whom it may concern:

Be it known that I, HARRY ABRAMSON, a citizen of the United States, residing at Philadelphia, in the county of Philadelphia and State of Pennsylvania, have invented a new, original, and ornamental Design for Sad-Iron Grates, of which the following is a specification, reference being had to the accompanying drawing, forming part thereof.

The figure is a perspective view of a sad iron grate showing my new design.

I claim:

The ornamental design for a sad iron grate, as shown.

HARRY ABRAMSON.

Witnesses:
